A. HERSKOVITZ

MULTIPLE PLUG RECEPTACLE

Filed May 2, 1924

Inventor:
Abraham Herskovitz,
by Charles O. Sherry,
his Atty.

UNITED STATES PATENT OFFICE.

ABRAHAM HERSKOVITZ, OF NEW YORK, N. Y., ASSIGNOR TO PEERLESS LIGHT COMPANY, OF CHICAGO, ILLINOIS, A CORPORATION OF MAINE.

MULTIPLE-PLUG RECEPTACLE.

Application filed May 2, 1924. Serial No. 710,493.

To all whom it may concern:

Be it known that I, ABRAHAM HERSKOVITZ, a citizen of the United States, and a resident of New York, Bronx County, and 5 State of New York, have invented certain new and useful Improvements in Multiple-Plug Receptacles, of which the following is declared to be a full, clear, and exact description.

10 This invention relates to multiple plug receptacles, and its principal object is to provide a simple, practical and comparatively inexpensive device containing a plurality of plug jacks into which terminal plugs 15 may be plugged for making electrical contact for conductor cords; and which device, itself, may be plugged into a wall or floor receptacle of many of the ordinary and well known types. Another object is to reduce 20 the number of parts to a minimum, to simplify the construction and assembling thereof and to otherwise improve thereon. To such ends this invention consists in the several novel features hereinafter fully set 25 forth and claimed.

The invention is clearly illustrated in the accompanying drawing, in which:—

Fig. 1 is a perspective view of a multiple plug receptacle, embodying a simple form 30 of the present invention, a wall receptacle and a push and pull plug cap, showing the parts disconnected; Fig. 2 is a perspective view of the multiple plug receptacle with its case partly broken away; Fig. 3 is a detail, 35 horizontal section through the device; Fig. 4 is a vertical cross section taken on line 4—4 of Fig. 3 and Fig. 5 is a side elevation showing a slightly modified form of the invention.

40 Referring to said drawing and first to Figs. 1 to 4 inclusive which illustrate a simple embodiment of the present invention, the reference character 10, designates a rectangular case or housing formed of 45 fibre or other non-conducting material. Preferably said case is composed of end wall members 11, 12 and a top, bottom and side wall member 13. Each end wall member 50 11, 12 is formed with a groove 14, which runs parallel with the marginal edge of the member and the ends of the top, bottom and side wall member 13 fit into said groove. The three members of the case are fastened 55 together by the plug jack units, as will hereinafter appear. The top, bottom and

side wall member 13 is made of a relatively thin sheet of insulating material shaped up into rectangular form as shown with its opposite edges 14^a, abutting against each other.

In the end wall 11 and top and bottom walls of the case are formed holes a, b, c, through which the contact pieces of push and pull plug caps are inserted for making electric connection in the receptacle.

Secured to the end wall member 11, as for instance by rivets 15, is a pair of plug jack units 16, constructed and arranged with contact pieces 17 for connection with a wall receptacle 18 and having a plurality of 70 jacks 19, 20, 21, into which a plurality of push and pull plug caps may be plugged in. A simple form of push and pull plug cap is shown at 22. The construction of the plug jack units 16 will now be described.

75 Each unit 16, comprises a metal strip 23 which extends lengthwise of the case, and has a bent end portion 24 at one end which is secured to the inner face of the end wall member 11, by the rivet 15. The other end of the strip 23 protrudes out through a hole 25 in the end wall member 12 in the form of a terminal contact piece 17 which may be inserted into the jack of the wall receptacle 18. The metal of the strip 23 is upset slightly at the outer face of the end wall member 12 as at 27 and said upset part forms a shoulder that bears against the outer face of said member 12, to secure the wall members of the case together.

80 Approximately midway between the end wall members, a metal tongue 28 is secured to the strip 23 and extends parallel therewith toward the end wall member 11. Beyond the place of securement of said tongue 85 to the strip 23 the two are bent apart slightly as shown, to leave a slight space therebetween for the reception of a terminal contact piece of a push and pull plug cap. The extreme end portion of the tongue 28 is 100 bent away from the strip as shown to facilitate the insertion of a terminal contact piece. The tongue 28 and adjacent portion of the strip 23 form one jack member 19 of the pair which receives the terminal contact pieces of a push and pull plug cap inserted through the holes a, in the end wall member 11 of the device.

105 Approximately midway between the end wall members 11, 12, and extending at right 110

angles to the strip 23 is a pair of metal strips 29 that extend across the sides of the strip 23 and tongue 28, and form the jacks 20, 21. The strip 23, tongue 28 and tongues 29 are rigidly secured together by a rivet 30. The strips 29 are bent toward each other slightly above and below the strip 23 and tongue 28 so as to grip the push and pull plug cap terminal contact pieces that are inserted between them through the holes *b* and *c* in the top and bottom walls of the case. The extreme end portions of the strips 29 are curved outward slightly to facilitate the insertion of the terminal plug cap contact pieces.

The two jack units, 16 are spaced apart the proper distance to accommodate the usual terminal contact pieces of push and pull plug caps and to permit the contact pieces 17 to be plugged into a wall receptacle 18.

In use the device may be plugged into the usual wall or floor receptacle adapted for push and pull plug caps, thereby accommodating said receptacle to several push and pull plug caps. The metal strips and tongues of the device establish electrical connection between the terminals of the wall receptacles and plug caps that are plugged into the device.

In the form illustrated in Fig. 5, the two plug jack strips 23^a are secured respectively to the screw shell 19^a and centre contact piece 19^b of an electric socket and the tongues 29^a are secured to the strips 23^a. The screw shell and plug jacks are contained in a case or shell 10^a of insulating material, and the strips 23^a project therefrom whereby the device may be plugged into a wall receptacle.

In this form of the invention, the receptacle may serve to hold an electric light bulb, which may be screwed into the screw shell 19^a or a screw plug may be plugged into it. The ordinary push and pull plug cap may be plugged into the receptacle as in the preferred form.

The device is simple, not likely to get out of order, is comparatively inexpensive, is light, compact and highly efficient for the purpose intended.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A multiple plug receptacle comprising a housing having a side wall and end walls

made of insulating material, and plug jacks in said housing and secured to one end wall, having contact parts protruding therefrom, said plug jacks having means engaging the other end wall to solidly close said housing. 65

2. A multiple plug receptacle comprising 70 a housing having a side member and end members made of insulating material, and jack units in said housing and fastened at one end to one member of said housing, the other end member being arranged to be slipped over said jack units 75 to close the housing, and said jack units having means to lockingly engage the end wall thereon.

3. A multiple plug receptacle comprising 80 two grooved insulating housing members and a tubular insulating housing member seated in the grooves of said first mentioned housing members, jack units in the housing formed by said housing members, said jack units having protruding contact points, and having means to secure the grooved housing members upon the tubular housing member. 85

4. A multiple plug receptacle, comprising 90 a case formed of two grooved end wall members, and a tubular side wall member seated in the grooves of the end wall member and all composed of insulating material, and a pair of plug jack units, in said 95 case and secured to one end wall thereof, the other end of the plug jack units projecting beyond the other end wall, and having shoulders bearing against said other end wall to secure the parts of the 100 case together.

5. A multiple plug receptacle, comprising 105 a multiple part housing made of insulating material, a pair of plug jack units in said housing and secured thereto, and formed with a plurality of plug jack tongues for the simultaneous reception of a plurality of push and pull plug cap contact pieces, said units being also formed 110 with terminal tongues that project from the housing and are adapted to be plugged into a wall receptacle, and said tongues being formed with means for securing the several parts of the housing together. 115

6. In a multiple plug receptacle, a plug 115 jack unit comprising a strip of metal, a tongue secured thereto and extending parallel therewith to form spaced contact pieces of a plug jack, and a pair of spaced tongues extending at right angles to said strip, one on each side thereof and secured thereto, said pair of tongues forming additional plug jacks. 120

Chicago, Ill., April 28, 1924.

ABRAHAM HEESKOVITZ.
